WITNESS:

UNITED STATES PATENT OFFICE.

ANTON HELFRICH, OF MILWAUKEE, WISCONSIN.

AUTOMATIC NAIL-CLAMP ATTACHMENT FOR HAMMERS.

Application filed February 19, 1927. Serial No. 169,590.

The object of this invention is the provision of a hammer with an automatic nail holder or clamp of an extremely simple but thoroughly efficient nature.

5 A further object is the provision of an automatic nail clamping attachment for hammers which is not only efficient for clamping nails against the eye portion of a hammer head, so that the nail may be started 10 in the work in which it is to be driven but which will readily release a nail when the same is to be operated on by the hammer, and further wherein the device serves as a 15 protector for the portion of the handle at and adjacent to its connection with the hammer head.

To the attainment of the above broadly stated objects and others which will present themselves as the nature of the invention is 20 better understood, the improvement also resides in certain other novel features of construction, combination and operative association of parts, a satisfactory embodiment of which is disclosed by the accompanying 25 drawings.

In the drawings:

Figure 1 is a side elevation illustrating the application of the improvement.

Figure 2 is a similar view on an enlarged 30 scale with parts broken away and parts in section.

Figure 3 is a perspective view of the body portion of the improvement.

Referring now to the drawings in detail, 35 the numeral 1 designates a hammer head and 2 the eye portion thereof. In the eye there is received the end of the usual wooden handle 3.

In carrying out my invention I bore a hole 40 in one edge of the handle 3 in a line with the poll end of the hammer head and a suitable distance away from the eye 2 of the hammer head. This hole provides a pocket for one end of a comparatively light helical 45 spring 4.

The improvement comprises a metal member or plate 5 which is arched in cross section. The plate 5, at one end thereof, has its central portion extended and the said extension is formed with a V-shaped opening so 50 that the said extension provides a claw or a pair of jaws 6. The body of the member 5, at approximately the center thereof, has an opening 7 therethrough, and through this

opening there is passed a screw 8, the screw 55 entering the handle 3 and the head thereof resting against the wall provided by the opening 7. The screw thus provides a fulcrum for the member 5. The outer end of the spring 4 bears against the inner face of 60 the plate or member 5 to influence its claw end 6 into contact with the eye portion 2 of the hammer head 1. The claw 6 is disposed at a slight outward angle with respect to the body 5 of the device. This permits of the 65 insertion of the head of a nail between the claw 6 and the metal eye 2 of the hammer head 1, so that the nail is effectively held and initially driven by manipulating the 70 hammer in the usual manner. When the 75 nail is sufficiently started in the work the hammer is moved longitudinally to bring the head of the nail out of engagement with the claw and the nail is then finally driven home in the usual manner.

My improvement may be readily attached to any ordinary type of nail driving implements and is not, of course, to be restricted to employment in connection with claw hammers as disclosed by the drawings. The improvement in addition to automatically clamping a nail for initial driving, serves 80 as a protector for the part of the wooden handle on which it is arranged.

Having described the invention, I claim:

The combination with a hammer head having a wooden handle and said handle having a pocket therein arranged in a plane with the poll of the hammer head, of a metal plate which is arched in cross section to 90 loosely embrace the handle of the hammer and which plate has one of its ends centrally formed with a claw extension, said plate having a central opening therethrough, a screw passing through the opening and threaded into the handle and a helical spring 95 in the pocket exerting a pressure against the plate at one end thereof to swing said plate on its fulcrum to bring the claw against the eye portion of the hammer head and whereby a nail engaged by the claw will have its head portion forced against the eye of the hammer and sustained at a right angle with respect to the said eye portion of the hammer.

In testimony whereof I affix my signature.

ANTON HELFRICH.
